PRESSURE-SEATED CLOSURE

Forest C. Barber, Bartlesville, Okla.

Application May 12, 1938, Serial No. 207,542

7 Claims. (Cl. 266—39)

This invention relates to a quick-acting, pressure-seated closure for open-mouthed vessels, and more particularly to closures for use in connection with various smelting operations where molten metals are to be retained in a vessel and hot and corrosive gases are not to be retained.

It is an object of this invention to provide a simple, efficient, and durable pressure-seated closure.

10 It is a further object of this invention to provide a closure which can be readily and quickly opened and closed.

Another object of this invention is to provide a closure for a vessel which is substantially on its side, the said closure being in a vertical position and adapted to retain certain of the contents of the vessel while at the same time allowing other contents of such a vessel to pass.

20 A further object of this invention is to provide a closure for a container which has within it materials at a high temperature.

Still another object of this invention is to provide a closure which comprises or which has incorporated with it a material suitable for thermal insulation and also suitable as a gasketing material.

Further objects and advantages of my invention will become apparent as the disclosure and discussion proceed.

30 In the smelting of zinc ore to produce the metal in an uncombined form, zinc ore and coke in a finely divided or pulverized form are intimately mixed and heated together. A chemical reaction takes place involving these materials and zinc is released from chemical combination with other elements. The zinc can be obtained as a product of this reaction in a substantially pure metallic form except at it may be more or less contaminated by other metals which may be present as components of the ore.

In commercial practice this chemical reaction, or smelting, is often carried out in a relatively small retort, which is frequently a cylinder about one foot in diameter and about six feet long and closed at one end. This cylinder has walls about an inch thick which are composed of baked clay, or other ceramic material, which is quite resistant to high temperatures and the destructive action of hot corrosive materials, such as molten or vaporized metals. This retort is placed in a furnace with its long axis substantially horizontal, the closed end being within the furnace and the open end being at the edge of the furnace and substantially flush with the outer wall thereof. This outer, open end is preferably

slightly lower than the inner, closed end so that any liquid material such as molten metal which may at any time be within the retort will tend to flow out of the retort and yet any solid material such as unreacted ore or coke, or cinders and the like, which remain after reaction, will not tend to slide out of the retort by the force of gravity.

As a result of the high temperatures which exist within this retort, the zinc or other metal produced by the smelting of the ore therein will be at or near its boiling point and therefore will have an appreciable vapor pressure and substantial amounts will exist in the vapor state. In order to be collected the metal vapor must be condensed, much as the vapor of any other material which it is desired to recover, and for this purpose a condenser is used in cooperation with the aforementioned retort. This condenser is made of a temperature-resistant ceramic material which is similar to or the same as the material from which the retort is made. This condenser has the form of a hollow, truncated cone about two and one-half feet long, with walls which are also about an inch thick. The base or larger end of this condenser has essentially the same dimensions as the open end of the aforementioned retort, against which it is fitted more or less snugly. The smaller end of this conical condenser is about two and one-half or three inches in diameter. The condenser rests upon brackets or the like, with its axis also substantially horizontal, but with enough of an angle therefrom so that the bottom portion of the smaller end is slightly lower than the bottom portion of the larger end. Free metal in a substantially molten state collects in this condenser, running into it from the retort and condensing from the gases and vapors which leave the retort and pass into and through the interior of the condenser toward the smaller end thereof.

It has heretofore been the practice of the art partially to close or dam the small end of this condenser with a handful, more or less, of dampened granular material such as cinders or the like, leaving a small hole or unclosed portion near the top part of the condenser through which pass gaseous reaction products of the smelting operation, somewhat cooled in the condenser and freed of substantially all of the metal vapors. This handful of material must of necessity be put in place by hand, and whenever it is desired to draw off the molten metal which has collected in the condenser, this dam must be removed completely. In doing this, the dam material and molten metal are raked or scraped

into a ladle, the dam material floating on top of the metal and being removed from time to time as collection of metal from large numbers of individual retorts proceeds.

5 I have now invented a device which is easily and quickly attached to the end of such a condenser, which will hold back the molten metal while allowing undesired vapors and gases to escape, which may be easily and repeatedly opened 10 and closed without undue effort, which is substantially immune to the corrosive and destructive action of high temperatures and molten metals, and which possesses other advantages over the prior art.

15 Various features of my invention will now be described in connection with the accompanying drawings which form a part of this specification, and which show diagrammatically two modifications of my invention.

20 Referring now to the drawings:

Fig. 1 is a front plan view of one form of my invention showing the cover in an open position.

25 Fig. 2 is a side plan view of the same modification of my invention.

Fig. 3 shows another modification of my invention and also shows the cover in an open position.

30 Fig. 4 shows a side plan view of the modification of Fig. 3 and shows the cover in a closed position.

Referring now more particularly to Figs. 1 and 2, 10 is the smaller end of a condenser such as hereinbefore described and 11 is the open mouth or end thereof. Encircling the end of this condenser and adjacent to said end is a band 12, the ends of which are secured by a clamp 13. This clamp 13 can be adjusted by a screw 14 and a nut 15 cooperating therewith, said screw passing 35 through a hole 16 in a lug or ear 17 attached to one end of the band 12, so that when once adjusted the closure assembly may be readily removed from and securely attached, or re-attached, to the end of a condenser by suitable and simple 40 manipulation of the clamp 13. Attached to the outer edge of the band 12 are lugs 18 which preferably extend only over a part of the thickness of the wall of the condenser 10. A cover 20 is attached to band 12 by a hinge or other pivotal means 21. The outer edge of this cover 20 should have substantially the same size and shape as the outer edge of the end of the condenser 10. Two lugs 22 and 22' are securely attached to or form 45 a part of band 12 and are located on either side 50 of and adjacent to the hinge 21. Two other similar lugs 23 and 23' are attached to the cover 20, one on each side of said cover and preferably 55 so located that they are an appreciable distance below the lugs 22 and 22' when the cover is closed, a position not shown in either Fig. 1 or Fig. 2, but 60 one readily understood from the drawings. A tension spring 24 joins lugs 22 and 23 and a similar tension spring 24' joins lugs 22' and 23'. A 65 layer of thermal insulating material 25 covers most of the inner surface of the cover 20 and is securely attached thereto by means not shown. This layer of insulating material 25 should have 70 essentially the same shape as the opening of mouth 11 of the condenser 10 and should have an appreciably larger area than the said mouth. A lug 27 may be attached to the cover 20 substantially 75 opposite the hinge 21, with the end thereof projecting from said cover and pointing away from the center of the cover. When desired, this lug 27 serves as a handle, and preferably does not

project beyond the periphery of the cover 20. A vent hole 28 passes through the cover 20 and the insulation 25. This vent hole is located between the center of said cover and the hinge 21, so that when the cover is in a closed position this vent 5 will be in the upper portion of the cover, preferably with one edge of the vent hole coinciding with the upper, inner edge of the end of the condenser. Preferably a strip of the thermal insulating material 25 is attached to the cover 20 10 between the vent hole and the hinge 21 so that said hinge is protected from fumes which pass from the condenser 10 through this vent hole and which would tend to pass between the cover and the end of the condenser if such strip were not 15 present.

As used at present, the condenser 10 is in the shape of a truncated circular cone and as such has sloping sides as illustrated. The band 12 has accordingly been illustrated in a manner such as 20 to conform with these sloping sides, the edge 29 of the band being a little shorter than the edge 29'. It will of course be obvious that the condenser 10 can be provided with a shoulder or neck at this end, a modification not illustrated, and 25 that the band 12 can be made in any convenient shape so as to conform with and securely fit such a neck or shoulder. The nut 15 and the screw 14 can be adjusted so that when the clamp 13 is closed, the band 12 fits securely around the end 30 of the condenser 10 and attaches the closure assembly rigidly to said condenser. The lugs 18 which have been illustrated will not always be necessary, especially if a shoulder such as that just mentioned is used, although under certain 35 conditions they are an aid to the quick and accurate adjustment of the band 12 when it is being fitted to the end of the condenser. The outer edge of the insulation 25 has been illustrated as being sufficiently restricted so as not to touch the 40 lugs 18 when the cover is in a closed position. However, if such lugs are used, the insulation 25 may project sufficiently to cover the ends of said lugs provided notches or indentations are made in said insulation so that the lugs will not prohibit 45 the surface of the insulation from making contact with the end of the wall of the condenser.

Referring now to Figs. 3 and 4, another modification of my invention is illustrated. In this modification, in place of the band 12 of Figs. 1 and 2, there is incorporated in the condenser 10 when 50 it is made an attachment means which will now be described.

A plate 30 lies within the wall of the condenser with one end of the plate a short distance from 55 the end of the condenser. This plate has a hinge arm 31 projecting forwardly from one side of it near the forward end and a similar hinge arm 31' projecting from the other side of it and at the same end. These hinge arms 31 and 31' are substantially in a parallel relationship and are spaced apart from each other and together form a fulcrum. Rigidly attached to the top portion of the cover 20 and on each side of the vent hole 28 are hinge arms 32 and 32', which are attached to 60 said cover by any suitable means such as the rivets 35. These hinge arms are substantially parallel to each other and are spaced apart from each other and arranged in co-acting relation to the hinge arms 31 and 31'. Hinge arms 31 and 31' are pivoted to hinge arms 32 and 32' by hinge pins 33 and 33'. A pin 22'' forms a tie connecting the two hinge arms 31 and 31' together and similarly a pin 23'' forms a tie connecting the hinge arms 32 and 32'. A tension spring 24'' has one 70 75

end attached to pin 22" and the other end to pin 23", and is so arranged as to be under tension when the cover 20 is closed and to exert its force between these two pins, thereby drawing the cover 20 down tightly so that the insulation 25 is in contact with the end of the wall of the condenser 10 as is shown in Fig. 4. As the cover 20 is opened, the spring 24" is stretched until the axis of the pin 23" lies on a straight line passing through the axes of the hinge pins 33 and 33' and the axis of the pin 22". As the cover 20 is further opened, the tension spring 24" contracts, tending to force the cover further open. The opening movement of the cover is stopped by a lug attached to each hinge arm 32 and 32' such as the lugs 34 and 34' illustrated. Said lugs 34 and 34' extend inwardly so as to contact the hinge arms 31 and 31' as the cover is opened and thus arrest further motion of the cover. In this position the tension spring 24" acts to hold the cover open. While the plate 30 is shown as a curved plate, it may of course be more or less flat as desired.

A baffle 36 may also be located between the vent hole 28 and the edge of the cover 20, with one edge substantially against the cover and positioned to project forwardly and upwardly when the cover is closed. This baffle serves to direct the fumes and flames which may issue through the vent hole 28 away from the hinge arrangement and especially away from the tension spring 24". This baffle 36 may be attached to the cover 20 by the same rivets 35 which attach the hinge arms 32 and 32', or it may be attached to and form a bridge between the hinge arms 32 and 32'.

Although such is not shown, it will be readily understood that a similar baffle may be placed between the vent hole 28 and the hinge or pivotal means 21, in the modification shown in Figs. 1 and 2.

Other details of the cover shown in Figs. 3 and 4 are essentially the same as hereinbefore described in connection with Figs. 1 and 2. While this modification of the hinge or pivotal means has been illustrated only in connection with attachment means 30 imbedded in condenser 10 when said condenser is formed, nevertheless it will be obvious to those skilled in the art that such a pivotal means can be used to cooperate between a band 12 and the cover illustrated in Figs. 1 and 2, in which case the lugs 22, 22', 23, and 23' and the two tension springs 24 and 24' and the hinge 21 would not be necessary.

When the cover is closed, the thermal insulating material 25 should contact the end of the condenser at all points and especially at the bottom half thereof. The nature of the molten material which is contained within the condenser is such that it has a relatively high surface tension and does not wet either the condenser or any ordinary thermal insulating material. For this reason it will not penetrate into small holes or imperfections and will not tend to leak out between the end of the condenser and the insulating material under ordinary conditions. The head on this molten material is not very great so that the force of an ordinary tension spring is sufficient to overcome the force of this head and to keep the cover closed.

The vent 28 needs to be of considerable size as illustrated so that vapors produced by the smelting operation will readily pass out of the condenser and in case these vapors still contain vapors of metal which would tend to condense

and solidify on the edges of the hole, such condensed material will not obstruct the hole to too great an extent. It may often be desirable to provide for the insulating material 25 to protect the edges of the vent hole 28. In this case the corresponding hole in the metal cover 20 will be somewhat larger than the actual size of the vent hole 28, and a ridge or lip of insulating material 25, surrounding the hole passing through the insulating material, will project through the hole 10 in the metal and serve to cover and protect the edges thereof. Such a modification is not shown in the drawings, but will be obvious to those skilled in the art.

The shape of the cover of my closure has been shown as being circular, which conforms with the cross section of the condenser as now used. However, it will be obvious that such a cover may be of any shape to conform best with the cross section of any condenser used.

The thermal insulating material 25 may be any such material which is inert to the action of the molten materials which may be present in the condenser 10, which is substantially unaffected by continued exposure to high temperatures and which has sufficient mechanical strength to withstand repeated openings and closings of the cover, such as asbestos board or other hard and compact mineral thermal insulating materials or certain fireclays and the like. As will be obvious to those skilled in the art, the thermal insulating material 25 may be attached to the cover 20 in any manner such as having the heads of rivets, not shown, imbedded in the insulating material, said rivets passing through corresponding holes in the cover 20 and being secured on the outside of said cover. If such thermal insulating material is of sufficient mechanical strength, it may also form the main part of the cover with the various hinges, lugs, etc., attached directly to it.

All those attachments which are made at the top, away from the molten metal, may be secured by means of rivets which pass through the said insulating material. I have found that one desirable method of attaching insulating material to a cover is to have a cover concave with respect to the condenser when closed, with lugs projecting from the said cover inside of said concavity, and then filling said concavity with a plastic thermal-setting ceramic material such as fire clay and subsequently heating said plastic material to dry and consolidate it, whereby it becomes a hard, coherent mass firmly attached to said cover. If such thermal insulating means is used, it can be readily replaced when necessary by breaking it up by a mechanical means and again filling the concavity with fresh plastic thermal-setting ceramic material in an unbaked plastic condition.

The various metal parts of the closure herein disclosed should be of materials which do not readily oxidize or corrode when heated to high temperatures in the presence of air or of corrosive gases such as sulfur dioxide. Although ordinary iron or steel may be used, special steel alloys are known, such as the so-called 18-8 chromium-nickel steels, which are quite resistant to corrosive action. The spring or springs used should especially be made of a steel which is relatively resistant to corrosion and which will retain its temper after considerable exposure to elevated temperatures, so that the tension of the spring will not decrease during continued use to too great an extent.

While I have illustrated and discussed only certain modifications of my invention, which I have

found to be preferable, I do not desire to restrict myself entirely to such modifications and it will be understood that certain obvious modifications and changes of details herein shown and described may be made by one skilled in the art without departing from the spirit of my invention as defined in the claims.

What I claim is:

1. A closure for an open-mouthed vessel, which comprises a cover comprising substantially solid thermal insulating material, means for attaching said closure to said vessel, means pivotally connecting said cover with said attaching means, at least one tension spring adapted to hold said cover against said vessel when closed and to hold said cover open when open, and a vent hole in said cover substantially on a line connecting the center of said cover and said means pivotally connecting said cover with said attaching means and between said center and said means, said cover being substantially in a vertical plane when closed.
2. A closure for a vessel with an open mouth, said mouth as defined by its edges being substantially in a vertical plane, which comprises an adjustable band adapted to encircle and firmly grip the outside of the mouth of a vessel, a cover for the mouth of said vessel, a hinge connecting said band and the upper portion of said cover and adapted to allow said cover to pass through an arc substantially greater than 90° between its closed and open positions, a tension spring means cooperating between said cover and said band normally holding said cover against the mouth of said vessel and adapted also to hold said cover in an open position and a vent hole passing through said cover and located between the center of said cover and said hinge.
3. A pressure-seated closure for a vessel with an open mouth, positioned substantially in a vertical plane, which comprises a cover, thermal insulating material covering substantially the entire inner surface of said cover, a fulcrum supported from the wall of said vessel, means joining said cover and said fulcrum, a tension spring cooperating between said fulcrum and said cover operating to hold said cover against the mouth of said vessel and to hold said cover open when open, and a vent hole directly through said cover and said insulation and positioned between the center of said cover and the edge adjacent to said cover.
4. A pressure-seated closure for the open mouth of a condenser used in the smelting of zinc ore, which comprises a cover for said mouth, an adjustable band adapted to encircle and firmly grip the end of said condenser adjacent to said mouth, pivotal means connecting said band and said cover, two lugs attached to said band, one on each side of said hinge, two lugs attached to the periphery of said cover, one on each side of said hinge, two tension springs, each with one end attached to a lug on said band and with the other end attached to the corresponding lug on said cover, said springs holding said cover firmly closed when closed and open when open, thermal insulation covering substantially the entire sur-

face of said cover next to said mouth and a vent hole in said cover and thermal insulation between the center of said cover and pivotal means.

5. A pressure-seated closure for a vessel with an open mouth positioned in a substantially vertical plane, which consists of an adjustable band adapted to encircle and firmly grip the outside of the mouth of a vessel, a cover for the mouth of said vessel, thermal insulating material covering substantially the entire inner surface of said cover, a hinge connecting said band and said cover at substantially the highest portion thereof and cooperating therewith, two lugs attached to said band, one on either side of said hinge, two lugs attached to said cover, one on either side of said hinge, two tension springs, each joining a lug on said band with the corresponding lug on said cover and acting to pull said lugs together and a vent hole passing through said cover and thermal insulating material and located directly below said hinge when said cover is in a closed position.

6. A pressure-seated closure for the mouth of a vessel, said vessel being subjected to being partially filled with a molten metal which is to be retained and with gases and vapors which are to be released, said mouth being substantially in a vertical plane and so positioned that substantially all of said molten metal and said gases and vapors tend to pass therethrough, which comprises a cover for said mouth, thermal insulating material covering substantially the entire surface of said cover next to said vessel and having substantially the same configuration as the open portion of the mouth of said vessel and an area greater than that of said open portion, a band adapted to encircle and firmly grip the outside of said mouth, a fulcrum supported from said band to be positioned near the top of said mouth, means joining said cover and said fulcrum and pivoting on said fulcrum, a tension spring joining said cover and said band normally holding said cover against said mouth and adapted to hold said cover open when not closed, an unobstructed vent hole passing directly through said cover and insulating material and positioned between the center of said cover and said fulcrum, and an upwardly projecting baffle attached to said cover between said vent hole and said fulcrum.

7. A closure for a vessel with an open mouth, said mouth as defined by its edges being substantially in a vertical plane, which comprises attachment means adapted to be firmly secured to the wall of said vessel outside of said mouth, a cover for the mouth of said vessel, a fulcrum supported from said attachment means and positioned near the top of said mouth, means joining said cover and said fulcrum and pivoting on said fulcrum, a tension spring means joining said cover and said attachment means normally holding said cover against said mouth and adapted also to hold said cover in an open position, and a vent hole passing through said cover and located between the center and top of said cover.

FOREST C. BARBER.
